UNITED STATES PATENT OFFICE.

JOHN Q. SHERMAN AND ALBERT W. METZNER, OF DAYTON, OHIO; SAID METZNER
ASSIGNOR TO SAID SHERMAN.

MANIFOLDING MACHINE.

Application filed June 22, 1921. Serial No. 479,624.

Our invention relates to manifolding devices wherein for one thing a web or webs of paper are printed in the machine with the desired designations and then passed over a support for receiving impressions made by hand either autographically or by a typewriting machine. It also relates to special devices for providing transfer material between plural webs of paper in such machines and automatically re-inking or impregnating the same. Also it concerns the printing of more than one web of paper with forms so arranged as to register with each other, in parts, to be written upon when 10 in superimposed position for this purpose, and to the numbering automatically of a web or webs, as they pass through the machine.

It is of course old to provide a small rotary hand press which operates by drawing 20 the paper to be printed over the face of a printing roll, thereby revolving the roll and causing the impression to be made. Our invention has as its object the provision of simple inking means for such a printing roll, and for utilizing a numbering device in connection with the roll. It also is our object to print and number more than one web of paper, numbering each succeeding form 25 on each web in consecutive order, and to bring similarly numbered webs in substantial registry over a paper feeding device and writing support.

Another object of our invention is to provide a simple and effective means for continuously impregnating with suitable transfer medium the material which is used to transfer impressions from one web to another in manifolding machines.

These objects we accomplish by that certain construction and arrangement of parts to be hereinafter more specifically pointed out and claimed.

In the drawings,

Figure 1 is a perspective detail showing 45 the transfer material feed in manifolding machines and our novel method of renewing and re-inking of such material.

Figure 2 is a perspective detail showing the printing mechanisms and paper feeding 50 devices, wherein we print, number and feed a plurality of webs of paper.

Figure 3 is a perspective detail of the transfer material box and structures making up the re-winding and re-inking mechanism.

Figure 4 is a detail perspective view of 55 the transfer material spindle.

Figure 5 is a detail perspective of the numbering mechanism.

It will be noted that we have shown the devices as embodied in what is known as 60 an autographic register, although this is not the only machine with which they will be of use. Thus the register is shown as having a frame 1 and base 2, in which frame is supported a writing support or tablet 3, 65 over which the webs 4 and 4' of paper pass.

At one side of the frame is mounted any desired trough 5, in which is set a roll of transfer material 6, said roll having a core or spindle 7 of special nature. This spindle 70 has reduced ends, one end 8 being plain cylindrical and the other having a bifurcated nature as at 9.

The transfer material passes over the writing table member, and is interleaved 75 between the various webs of paper which are to receive transfers of the impressions formed on the topmost web. It is then drawn onto another like spindle mounted in a larger box or trough 10 at the other side 80 of the frame.

As shown the stub shaft 11, supported in the sides of the frame, is equipped with an external beveled pinion 12, and mounted in a suitable bracket on the outer side of 85 the frame is a stub shaft 13 carrying a beveled pinion 14 meshing constantly with the pinion 12. The sides of the box 10 at the portion where the ends of the spindle are set are cut out slightly as at 15, and then formed with semi-circular journaling cuts or notches for the said spindle ends. The lid of this carbon box 10, as will be noted, has the other half journal members for these 90 spindle ends, and the stub shaft has an extension adapted to fit into the bifurcated end 9. The spindle will then be revolved when the handle 16 for the stub shaft 11 is operated.

Another method of forming the carbon 100 roll spindles, as shown to the right in Figure 4, is to provide a plain core portion 17

with reduced ends 18, one of the reduced ends having a knurled head thereon as at 19. This head can be manipulated by hand, and will not interfere with the mounting of the spindle in either carbon box, as the head will not interfere with dropping the spindle into the notched ends of either box.

In the box 10 it will be noted that there is formed a well 20 extending longitudinally 10 of the box, same being in the form of a trough closed except at the top. Journaled in the sides of the box in a position to have its periphery pass into the trough 20 is a roller 21, which contacts peripherally with another roller 22, mounted just above it in the sides of the box 10. This roller 22 may be about at the level of the writing table of the machine.

A friction roller 23 is provided which is 20 mounted with its ends 24 in slotted boxes 25 set into the upper end of the lid 26 of the box 10. The construction is similar to that widely adopted in autographic registers for the mounting of the upper or friction feed roller. The boxes house small springs 27 which engage on the ends of the roller and tend to press it down.

The lid 26 is hinged at 27^a to the outer wall of the box 10 and cut away so as to 30 permit the carbon material to pass from the writing table in between the friction roller 23 and the roller 22. Thus when the lid is closed the friction roller 23 will press on the roller 22 and the action of the rewinding of the carbon material onto the spindle 7 will cause the rollers 22 and 21 to revolve. When these rollers revolve the lower roller 21 will pick up ink or other impregnating fluid from the trough 20, 40 spread it over the roller 22 and this roller will spread the said fluid over the one side of the transfer material.

During the period when the paper is 45 stored on the spindle 7, the fluid will have the chance to work thoroughly into the body thereof, so that when a complete roll of the material has been used from the supply in the original box or trough, the renewed roll may be lifted from the rewind box 10 and 50 shifted to the supply box, whereupon the spindle in the supply box may be used for a rewinding spindle in the box 10, or the spindles can be removed and reinserted in same position if so desired.

While many various mechanisms might be used for providing the various feeding movement above described, we have selected as typifying our invention the simple form above set forth, and its advantages will be 55 obvious without special mention.

Referring next to the printing mechanism, which we have shown separate from the transfer material mechanism for purposes of clearness, it will be noted that the printing cylinder or roll 30 is mounted to

revolve idly on a spindle 31 journaled in the sides of the frame 1. Inset into this roll, which will have the desired set up of type, as in the usual printing cylinder, is a counter printer 32 of any desired type, 70 said counter being so set that the number type thereon will be at the printing surface of the roll with its shaft 33 journaled in the sides of the cylinder. This operating shaft 33 of the counter will project beyond the 75 one side of the roll and will be equipped with a handle 34, which once during each revolution will strike a stop 35 set into the side frame 1, which will move the handle so as to turn the number printers to the next 80 consecutive number. In numbering devices of this character the handle 34 may be set loosely over the shaft 33 and will carry a pawl 36 resting against a ratchet 37 that is fast on said shaft 33. The handle will be 85 pulled to a normal position by means of a spring 38, so that when it strikes the stop 35 it will move the ratchet over one notch and then will return to its normal position ready for another operation. 90

In the drawings we have shown two supply rolls for paper as at 39 and 40 having lateral friction plates 39^a and 40^a. Hinged by means of arms 41 on a shaft 42 is the pressure roller 43 for the web 4 of paper. 95 The shaft 42 is journaled in the sides of the frame 1 and a spring 44 may be mounted on the side frame to bear against one of the arms 41.

Thus the web of paper 4 coming from the roll 39 will be passed up and around the roller 43 and thence between the roller and the printing surface of the printing roll. It will then pass downwardly and over suitable idler spindles 44^a which lead it up to 105 the level of the writing table of the machine. These spindles may be made up of the cylindrical portions marked 44^a, which are mounted on long pins 45 that may be thrust through holes (not shown) left in the side 110 frame.

The other web of paper 4^a passing from the roll 40 is provided for in the same way as above described with a pressure roll 46 spring-pressed as at 47 against the surface 115 of the printing roll. Idlers 48 set into the frame will then lead this web into a position level with the writing table, the spacing of these idlers being such as to give a path of the correct length to the webs 4 and 4^a, 120 so that the printed marks and lines will be aligned with each other as the webs pass the last idler 48 for the web 4^a.

Any desired form of feeding device for paper may be provided with the machine, such as the friction roller 49 and the driven friction feeding disks 50. As this special mechanism forms no part of the invention, we have shown no detail in this feeding device, but include any desired form of friction 125 130

or gripper feed for the paper, such that it will be forcibly drawn over the writing table.

Referring to the operation of the parts now described it will be noted that the act of drawing the webs along through the machine will cause the printing roll to revolve, since the webs are pressed against it. This will result in a printing on the webs of whatever type or stencil is formed on the printing roll.

For inking the printing roll we provide a device somewhat similar to that described for the carbon material. Thus a trough 51 is set in the side frame pieces of the machine, and an idler roller 52 likewise mounted to revolve in the mouth of the trough. Some such construction as described for the roller 21 will suffice.

The ink spreading roller 53 is set into the side frame of the machine in such a way as to bear against the printing surface of the printing roll, but its full diameter should not extend out far enough to allow the handle on the numbering device to contact with it as the printing roll revolves. As shown the spindle 54 of this roll is not large enough to strike the handle.

A shaft 55 mounted in the side frame of the machine carries arms 56 that journal in their ends a roller 57. The arrangement is such that when the shaft 55 is permitted to take one position, the roller 57 lies against both the roller 53 and the roller 52, and will transfer ink from the latter to the former, as well as act as a driver to impart motion to the latter from the former.

The shaft 55 is equipped with a plate at one of its ends, which plate has a hook portion 58 under influence of a spring 59 that will pull the shaft to the position above described, for introducing the roller 57 into its active position. The plate has a handle portion 60 and another hook 61 on the side of the handle. A spring latch 62 will engage this hook 61 when the handle is pushed down, and when this has been done the roller 57 will be held in an inactive position.

It follows that when the printing roll is caused to revolve by the force applied to the paper the system of rollers down to the inking trough will all revolve owing to their contractual relation, except when the roller 57 is latched out of contact. The operator by controlling this latching of the roller 57 may permit an inking to take place of the printing roll whenever he desires and stop it when he desires.

For convenience the shaft 55 is extended out through the side frame (a fragment of 60 which is shown in Figure 2) and the latch and spring device mounted on the outside of the frame, so as to be readily available.

Having thus described our invention, what we claim as new and desire to secure by Letters Patent, is:—

1. In a printing and manifolding machine, the combination with storage devices for paper, of a printing cylinder, a numbering device carried thereby, means for changing 70 numbers each revolution of the cylinder, means for causing a plurality of webs of paper to press against the cylinder at different points, means for feeding said strips of paper through the machine, a platen or writing table element over which the paper passes, and means for enforcing a path to the paper after leaving the printing cylinder which will bring the webs thereof to alignment over the writing table with relation to the printed matter impressed thereon by the cylinder with like numbered sections superimposed on each other.

2. In a printing and manifolding machine, the combination with storage devices for paper, of a printing cylinder, a numbering device carried thereby, means for changing 80 numbers each revolution of the cylinder, means for pressing a plurality of webs of the paper against the cylinder at different 90 points, means for feeding said webs of paper through the machine, said cylinder being rotated by the friction of the paper against it, a platen or writing table element over which the paper passes, and means for enforcing a path to the paper after leaving the printing cylinder, which will bring the webs thereof to alignment over the writing table with relation to the printed matter impressed by said cylinder with like numbered 100 sections superimposed on each other.

3. In a manifolding machine, storage means for a plurality of webs of paper, a single printing and numbering means adapted to imprint all of the webs of paper with 105 a series of like forms and to number the forms consecutively, a writing table or platen, and feeding means for leading the webs of paper to the platen adapted to bring like numbered forms into alignment on said 110 platen and an operating member connected to feed the paper and operate the printing and numbering means.

JOHN Q. SHERMAN.
ALBERT W. METZNER.
